Baldwin Lahr
ATTORNEY

UNITED STATES PATENT OFFICE.

PHILIP H. PIERSON, OF SAN FRANCISCO, CALIFORNIA.

HOSPITAL-BED.

1,359,100.

Specification of Letters Patent. Patented Nov. 16, 1920.

Application filed April 17, 1919. Serial No. 290,689.

To all whom it may concern:

Be it known that I, PHILIP H. PIERSON, a citizen of the United States, and a resident of the city and county of San Francisco, 5 State of California, have made a new and useful invention—to wit, Improvement in Hospital-Beds; and I do hereby declare the following to be a full, clear, concise, and exact description of the same.

10 This invention relates to a new and novel appliance adaptable to hospital beds.

It is well known that in beds used in hospitals, it is often necessary to raise the body of the patient, and in many instances it is 15 impossible to touch the person lying thereon.

The object of this invention is to raise the head of the bed by means which will be convenient for either the attendant or the person lying therein.

20 Another object is to construct a bed of this character which will be free from complicated parts, and which will be so constructed that it will not be in the way of the attendant in leaning over the patient.

25 Another object is to make a bed which will accomplish this purpose and yet be very simple, as all hospital appliances must be as plain as possible.

In this specification and the annexed 30 drawings, the invention is illustrated in the form considered to be the best, but it is to be understood that the invention is not limited to such form, because it may be embodied in other forms, and it is also to be understood that in and by the claim following the 35 description, it is desired to cover the invention in whatsoever form it may be embodied.

In the accompanying drawings,

Figure 1 is a side elevation of my improved bed.

Fig. 2 is a plan view of the same looking from underneath.

Fig. 3 is a detail view of the hand wheel.

45 The numeral 5 designates the usual foot board, and the numeral 6 the usual head board. These boards are connected by longitudinal members 7 and 8 common in all beds.

50 The numeral 9 designates any form of spring stretched between the head and foot boards. Overlying said spring member, I provide substantially U-shaped members 10 and 11, which pass under the mattress along the sides thereof, and have their ends terminating in depending curved sections 12

and 13. These curved sections are hinged as at 14 and 15 to the side rails 7 and 8 of the bed proper. Cross members may be attached to said U-shaped members from one longitudinal side to the other passing under the 60 mattress and forming additional support to the same. These longitudinal members may be made of fabric or any other suitable material. Beneath the bed and parallel to the side members are rods 16 and 17 secured 65 in the head and foot boards, carrying at their forward ends bevel gears 18 and 19, which bevel gears mesh with gears 20 and 21 of a cross shaft 22, which cross shaft is journaled on the side members 7 and 8. The rear 70 ends of the rods 16 and 17 are screw threaded as at 23 and 24, and carry thereon internally threaded collars 25 and 26 to which is attached a cross rod 27. At the outer ends of the rod 27, I provide pivoted links 29 75 and 30 which are connected at their forward ends to the U-shaped member 11 at 31.

Upon one end of the cross shaft 22, I attach a gear 32 which meshes with a gear 33 carried by a hand wheel 34. This hand 80 wheel is pivotally mounted so as to rotate and is carried by one of the frame members. The U-shaped member which passes under the foot of the mattress is provided with a depending U-shaped member 35 hinged at 85 36 and adapted to rest in ratchets 37 provided upon the forward end of each member 7 and 8. It will now be seen that by this construction I can raise either end of the bed as necessity arises.

90 Assuming that a patient is lying upon the bed, and desires to raise himself to the position shown in dotted lines, Fig. 1 and indicated by the numeral 38, the hand wheel 34 is grasped and rotated which imparts 95 movement to the cross shaft 22 through the medium of the gear 32. This in turn rotates the shafts 16 and 17 through the bevel gears 18 and 19, 20 and 21. As these shafts 16 and 17 are rotated, screw threaded collars 100 25 and 26 are drawn toward the shaft 22. This in turn draws the link into the position shown in dotted lines in Fig. 1, thus causing the head section of the bed and mattress supported thereon to be lifted. The 105 foot section may be lifted by raising the U-shaped frame by hand, and it will stay in such a position through the action of the depending U-shaped member 35 co-acting with the ratchet member 37.

Having thus described my invention what I claim as new and desire to secure by Letters Patent of the United States is:—

The combination with a bed having head and foot boards connected by side rails, of a substantially U-shaped frame having its free ends pivotally mounted, respectively, to the side rails at substantially medial points thereof, a shaft extending transversely of the bed and journaled at its ends to said side rails at substantially medial points thereof, a pair of parallel shafts extending longitudinally of the bed and each disposed adjacent one of said side rails, at least one of the ends of said parallel shafts being journaled in one of said boards and means supporting the other end portions of said shafts, intermeshing gears on said

parallel and transverse shafts, said parallel shafts being threaded at least for a portion 20 of their length, collars threadedly adjustable on each of said parallel shafts, a transverse rod connecting said collars and having its free ends bent to extend substantially longitudinally of the bed and connected at 25 their extremities to the opposite legs of said U-shaped frame, and a hand wheel at the end of said transverse shaft for operating said shaft.

In testimony whereof, I have hereunto 30 set my hand at San Francisco, California, this 31st day of March 1919.

PHILIP H. PIERSON.

In presence of—
A. J. HENRY.
